UNITED STATES PATENT OFFICE

2,543,490

LEG OPERATED STEERING DEVICE FOR
OUTBOARD MOTORS

James M. England, Lebanon, Mo.

Application October 4, 1948, Serial No. 52,663

3 Claims. (Cl. 115—18)

1

This invention relates to outboard motors, and has particular reference to a leg operated device for moving an outboard motor so as to steer a boat on which the outboard motor is mounted.

An object of the invention is to provide a simple and efficient device adapted for attachment to the steering handle of an outboard motor whereby the helmsman of a boat on which the motor is mounted may use a leg to steer the boat and thereby have his hands free for fishing purposes, etc.

A further object of the invention is to provide an attachment for the steering handle of an outboard motor, whereby the helmsman of the boat on which the motor is mounted may utilize his leg for steering the boat while said helmsman is in a standing position within the stern of the boat.

Still another object is to provide an attachment of the above kind which is comparatively simple and durable in construction, easy to install, and efficient in use.

The exact nature of the present invention, as well as other objects and advantages thereof, will become apparent from the following description when considered in connection with the accompanying drawing, in which:

Figure 1 is a fragmentary perspective view showing an embodiment of the present invention in use;

Figure 2 is an enlarged plan view of an attachment embodying the present invention for use as shown in Figure 1;

Figure 3 is a fragmentary section taken on the line 3—3 of Figure 2;

Figure 4 is a fragmentary section taken on the line 4—4 of Figure 2.

Referring in detail to the drawing, 5 indicates a boat having a conventional outboard motor 6 mounted on the transom 7 thereof in the usual way by means of a bracket 8, said outboard motor having the usual laterally and rearwardly extending steering handle 9. The numeral 10 indicates the usual seat provided in the stern of the boat.

The illustrated embodiment of the present invention consists of an attachment for the steering handle 9, said attachment including an angular bracket 11 provided with a rearwardly projecting fork 12 at one end and adapted for rigid attachment at its other end to the steering handle 9, said fork being capable of embracing the leg of a helmsman below the knee so that the helmsman may operate the handle 9 by means

of his leg to steer the boat. Bracket 11 consists of an elongated strap iron member twisted at right angles intermediate its ends as indicated at 13 and having one end return-bent to provide spaced portions 14 and 15 having aligned openings, and a connecting portion 16 connecting the portions 14 and 15. The fork 12 has an elongated shank 16 which slidably extends through the openings of portions 14 and 15 so that the fork may be adjusted longitudinally of the boat. Means is provided to secure the fork 12 in adjusted positions, such means consisting of a bolt 18 extending freely through an opening of the connecting portion 17 and having an eye 19 embracing the shank 17, a wing nut 20 being threaded on the bolt 18 outwardly of the connecting portion 16. Obviously, by tightening the nut 20, the eye 19 may be caused to grip the shank 17 and thereby secure the fork 12 in adjusted positions relative to the bracket 11.

The bracket 11 is attached to the steering handle 9 by suitable means, such as a U-bolt 21 adapted to snugly embrace the handle 9 near its free end and having its legs freely extended through spaced openings in the adjacent end of the bracket 11, wing nuts 22 being threaded on the ends of the U-bolt 21 for drawing the latter into tight gripping engagement with the steering handle 9. Due to the obtuse angle form of the bracket 11, it extends rearwardly and laterally from the handle 9 toward the longitudinal center of the boat and then transversely of the latter to a point substantially at said center, thereby presenting the fork 12 to the leg of the helmsman at a point where lateral balance of the boat may be maintained when the helmsman assumes a standing position in the stern of the boat as shown in Figure 1. Also, the fork will be disposed at such an elevation that it will embrace the helmsman's leg slightly below the knee when the foot of the same leg is rested upon the seat 10, as shown. Thus, the helmsman may laterally shift his leg which is engaged in the fork 12 to thereby move the motor 6 and properly steer the boat. By using the present attachment, the helmsman will have both hands free for fishing and other purposes. As the rear seats of different boats may be at different distances from the transoms of the boats, the fork 12 may be adjusted forwardly or rearwardly to suit the conditions presented by the particular boat in use. In other words, the fork may be disposed to properly embrace the helmsman's leg even though he may be required to stand at slightly different distances from the outboard motor, ac-

cording to the particular boat on which the motor equipped with the present attachment is mounted.

From the foregoing description, it is believed that the construction, operation and advantages of the present invention will be readily understood and appreciated by those skilled in the art. Modifications and changes in details of construction are contemplated, such as fairly fall within the spirit and scope of the invention as claimed.

Having described the invention, what is claimed as new is:

1. A leg operated steering device for an outboard motor having a laterally extending steering handle, comprising an angular bracket having means at one end to rigidly secure the same to the steering handle of the outboard motor so as to extend laterally and forwardly therefrom, and a forwardly projecting fork rigidly attached to the other end of said bracket and adapted to embrace the lower segment of a leg of a helmsman for operating said steering handle, said fork having a slidble shank for adjusting said fork relative to said bracket.

2. A leg operated steering device for an outboard motor having a laterally extending steering handle, comprising an angular bracket having means at one end to rigidly secure the same to the steering handle of the outboard motor so as to extend laterally and forwardly therefrom and a forwardly projecting fork rigidly attached to the other end of said bracket and adapted to embrace the lower segment of a leg of a helmsman for operating said steering handle, said other end of the bracket being return-bent to provide spaced portions having aligned openings and a connecting portion connecting said spaced portions, said fork having a shank slidble in said openings to adjust the fork relative to said bracket, and means to secure the fork in adjusted positions including a nutted clamping bolt

extending through said connecting portion and having an eye member embracing said shank.

3. A leg operated steering device for an outboard motor having a laterally extending steering handle, comprising an angular bracket having means at one end to rigidly secure the same to the steering handle of the outboard motor so as to extend laterally and forwardly therefrom, and a forwardly projecting fork rigidly attached to the outer end of said bracket and adapted to embrace the lower segment of the leg of a helmsman for operating said steering handle, said other end of the bracket being return bent to provide spaced portions having aligned openings and a connecting portion connecting said spaced portions, said fork having a shank slidble in said openings to adjust the fork relative to said bracket, and means for securing the fork in adjusted positions.
